(57) **CLAIM**

The ornamental design for a minifigure hat accessory, substantially as shown and described.

DESCRIPTION

FIG. 1 is a perspective view of a minifigure hat accessory showing my new design;

FIG. 2 is a top view thereof;

FIG. 3 is a bottom view thereof;

FIG. 4 is a left side view thereof, with the right-side view being a mirror image thereto;

FIG. 5 is a front view thereof; and,

FIG. 6 is a cross-section view taken in the direction of line 6-6 of FIG. 2.

The broken lines in FIG. 2 illustrate the cross-sectional cut lines that form no part of the claimed design.
